United States Patent Office

Des. 190,569

Patented June 13, 1961

190,569

CHAIR

Francis M. Mair, Kensington Park, Calif.
(1 Arlington Ave., Berkeley, Calif.)

Filed Dec. 1, 1960, Ser. No. 63,286

Term of patent 14 years

(Cl. D15—1)

F i g. 1

F i g. 2

F i g. 3

F i g. 4

FIGURE 3 is a side view of the chair illustrated in FIGURES 1 and 2; and

This application is a continuation-in-part of my earlier filed application Serial No. D. 57,679, filed September 25, 1959, which is now abandoned.

I claim:

The ornamental design for a chair as shown and described.
